UNITED STATES PATENT OFFICE.

CHARLES AUTENRIETH, OF PHILADELPHIA, PENNSYLVANIA, ASSIGNOR TO HIMSELF AND E. COLLINS, ASSIGNORS TO THOMAS HEATH, OF SAME PLACE.

DESIGN FOR CENTER-PIECE FOR CEILINGS.

Specification forming part of Design No. 5,097, dated July 11, 1871.

To all whom it may concern:

Be it known that I, CHARLES AUTENRIETH, of Philadelphia, county of Philadelphia, State of Pennsylvania, have invented or produced a Design for Center-Piece for Ceilings, of which the following is a specification:

The figure in the accompanying drawings represents my design for a center-piece for ceilings, the principal features of which are, the central ornamental medallion A, the circular molding B surrounding the medallion and composed of beadings *a a*, panels *b*, and rosettes *d*, and the outer foliated border C.

The ornamental minutiae of all these features are too clearly illustrated in the drawings to need description.

I claim—

1. The design for the central ornamental medallion A.
2. The design for the molding B.
3. The design for the outer foliated border C.
4. The design for the whole center-piece, including the medallion A, molding B, and border C.

In testimony whereof I have signed my name to this specification in the presence of two subscribing witnesses.

CHS. AUTENRIETH.

Witnesses:

JOHN M. ATWOOD,
N. G. READ.
